(57) **CLAIM**

The ornamental design for a connector to electromechanical programmer, as shown and described.

DESCRIPTION

FIG. 1 is front view of a connector to electromechanical programmer according to the present invention;

FIG. 2 is a top view of the connector to electromechanical programmer depicted in FIG. 1.

FIG. 3 is a right side view of the connector to electromechanical programmer depicted in FIG. 1, with the left side view being a mirror image thereof.

FIG. 4 is a bottom view of the connector to electromechanical programmer depicted in FIG. 1; and,

FIG. 5 is a perspective front, top and right side view of the connector to electromechanical programmer depicted in FIG. 1.
